US00D613312S

(12) **United States Design Patent**
Lopp

(10) **Patent No.:** **US D613,312 S**
(45) **Date of Patent:** **** Apr. 6, 2010**

(54) **POWER ASSIST MOTOR FOR BICYCLE**

(76) Inventor: **James Lopp**, 4024 Weber Ln., Floyds Knobs, IN (US) 47119

(**) Term: **14 Years**

(21) Appl. No.: **29/329,190**

(22) Filed: **Dec. 10, 2008**

(51) LOC (9) Cl. **15-01**

(52) U.S. Cl. **D15/1; D12/111**

(58) **Field of Classification Search** **D15/1-4; D13/101, 112-114, 122, 184, 199; D12/111, D12/114; 180/65.1, 65.24, 220, 272, 205-206, 180/216, 227-228; 280/288.1, 288.2, 288.3, 280/284-288, 278, 283-286**

See application file for complete search history.

(57) **CLAIM**

The ornamental design for a power assist motor for bicycle, as shown and described.

DESCRIPTION

FIG. 1 is a rear perspective view of my new design for a power assist motor for bicycle.

FIG. 2 is a rear view of my new design for a power assist motor for bicycle.

FIG. 3 is an enlarged left side view of my new design for a power assist motor for bicycle.

FIG. 4 is an enlarged right side view of my new design for a power assist motor for bicycle; and,

FIG. 5 is a top view of my new design for a power assist motor for bicycle.

The broken line showing of a bicycle is included for illustrating environmental structure only and forms no part of the claimed design.
